United States Patent Office.

JAMES WILKINSON, OF BOWLING GREEN, MISSOURI.

Letters Patent No. 78,167, dated May 19, 1868.

IMPROVEMENT IN LIFTING-JACK.

The Schedule referred to in these Letters Patent and making part of the same.

TO ALL WHOM IT MAY CONCERN:

Be it known that I, JAMES WILKINSON, of Bowling Green, in the county of Pike, and State of Missouri, have made certain new and useful Improvements in Lifting-Jacks; and I do hereby declare that the following is a full and clear description thereof, reference being had to the accompanying drawings, and to the letters of reference marked thereon.

This invention relates to a lifting-jack wherein a movable fulcrum is actuated by the lever that raises the weight in a vertical direction at each successive stroke of the said lever, in such a manner as to maintain the fulcrum at a uniform distance from the weight to be raised.

To enable those skilled in the art to make and use my improved jack, I will proceed to describe its construction and operation.

Figure 1 of the drawings is a front elevation of the improved jack.

Figure 2 is a transverse sectional elevation of the same.

Figure 3 is an inside elevation of one of the fulcrum-posts, and showing sections of the fulcrum-pins in their sockets.

The fulcrum-posts A are to be erected upon a platform, A¹, and have their top ends connected together by a cap-piece, A². Grooves a¹ a² a³ a⁴ are to be made in the inside faces of the posts A, for the reception of the fulcrum-pins b. The grooves a¹ a³ are formed in a regular succession of segmental curves, and have steps at the points x x, at the intersection of two curves. These steps cause the bottoms of the said grooves a¹ a³ to present a serrated section in elevation. The steps x x are cut squarely into the post in such a manner as to allow the pins b to rest upon them, and above each step the bottoms of the said grooves are bevelled forward sufficiently far to form the next step above. Between the points x x the grooves a¹ a³ are segments of circles, the segments in a¹ being described from the points x in a³ as centres, and the points x in a³ in turn serving for centres from which to describe the segments of a¹.

The double fulcrum-head B has four bearing-pins, b, which fit in the grooves a¹ a³ in such a manner as to rest on the steps x of said grooves, as shown best in fig. 3. These pins are arranged to slide into cavities in the head B, as shown by the broken-out section in fig. 1, which also discloses springs behind the said pins, that force the pins forward into the grooves, but yield sufficiently to allow the pins to retreat into the head, when moving up the incline between the steps, as is also shown in fig. 1. A lever, C, is inserted into the head B, and as its outer end is worked alternately up and down, first one side of the fulcrum-head, and then the other, is raised so as to allow the pins b to rest on the steps x, and in this manner both the lever and its fulcrum are raised with the weight, which may be placed on top of the prop D, or attached to the hook D'. When the fulcrum-block shall in this manner have been raised to the top of the grooves a¹ a³, the pins b will be pushed forward into the grooves a² a⁴, in which they will then slide down to the bottoms of the said grooves, and thence again into a¹ a³, where the raising operation may be repeated.

Having described my invention, what I claim, is—

1. The posts A A, when provided with the segmental serrated grooves a¹ a³, and combined with a movable fulcrum, B, substantially in the manner and for the purpose herein shown and described.
2. I claim the fulcrum-head B, when provided with the spring-bearing pins b, and otherwise arranged, as herein set forth and described.

In testimony of which invention, I hereunto set my hand, in presence of—

JAMES WILKINSON.
